UNITED STATES PATENT OFFICE.

JAMES C. KIMSEY, OF PHILADELPHIA, PENNSYLVANIA, ASSIGNOR TO AMERICAN PAPER BOTTLE COMPANY, OF PHILADELPHIA, PENNSYLVANIA, A CORPORATION OF PENNSYLVANIA.

PROCESS OF MAKING PAPER RECEP'TACLES.

No. 811,409.

Specification of Letters Patent.

Patented Jan. 30, 1906.

Application filed December 7, 1904. Serial No. 285,884.

To all whom it may concern:

Be it known that I, JAMES C. KIMSEY, a citizen of the United States, residing in Philadelphia, Pennsylvania, have invented Improvements in the Process of Making Paper Receptacles, of which the following is a specification.

The main object of my invention is to reinforce the open end of a paper cup or other receptacle and to form a shoulder thereon in order to prevent the cups becoming tightly jammed when nested.

A further object of my invention is to utilize part of the tube from which the cup is made, as the reinforcing-section.

Referring to the accompanying drawings, Figure 1 is a perspective view of a paper cup illustrating my invention. Fig. 2 is a vertical sectional view. Fig. 3 is a view showing the reinforcing-ring separated from the body of the cup. Fig. 4 is a view illustrating the method of cutting the sections from the tube, and Fig. 5 is a view showing a series of cups nested.

In the present instance the body of the cup is made tapered, being smaller at the base than at the open end. The body A is made from paper wrapped around a tapered former and closed at one end by a bottom B. This bottom is flanged at b, and the end a of the tube is turned under the flange and secured thereto by any adhesive material. When the tube is turned in, as shown, a locking-disk B', preferably also of paper, but somewhat heavier than the bottom of the cup, is forced into the space formed by the flange, so as to retain the turned-in portion a in position against the flange b of the bottom. This disk may be attached to the bottom by cement or other adhesive material, if desired. This method of securing the bottom to the body of the cup is illustrated and claimed in another application for patent, and therefore I do not claim it in this application.

When tapered cups are nested in the manner shown in Fig. 5, they tend to adhere one to another, and it is with great difficulty that they can be separated after remaining for any considerable length of time nested. To obviate this and to make the open end of the cup stronger, I place a reinforcing-ring D on the outside of the body A at or near the end, preferably directly at the end, and this ring

I can secure to the body by any suitable adhesive material.

Referring now to Fig. 4, I is a tube of any length desired. This tube in the present instance is cut on the lines $x x' x^2 x^3 x^4$, so as to make three body-sections A A' A² of different diameters, and between these body-sections are ring-sections D D' D².

The paper from which the cup is made is of such a taper compared to the thickness and the length of the ring-section that the body portion A can pass through the ring D and the ring will snugly fit the open end of the body portion, as indicated in Fig. 2, while the ring D' will fit the open end of the body portion A', and the ring D² will fit the open end of the body portion A². By this arrangement I provide a solid ring which will add great strength to the cup and at the same time form a shoulder which can rest upon the end of the cup with which it is nested, so as to prevent the body portion of the cups coming into such contact as to cause them to adhere one to another.

It will be understood that the ring may be made from a separate tube, if desired; but I find that the above-described method is the most economical in the manufacture.

While I have illustrated my invention in connection with a cup, it may be used also in connection with a bottle or other container, and while it is especially applicable to cups or other containers having tapered body portions it may be used to advantage on a receptacle having a body portion of an even diameter throughout.

I claim as my invention—

1. The process herein described of making a paper receptacle, said process consisting in forming a tapered tube of paper, of such a taper compared to the thickness of the same that a ring-section cut from the large end of the tube will fit snugly around the body at the large end thereof, cutting a ring-section from the large end of the tube, and passing the tapered tube through the ring and securing the ring to the periphery of the large end of the tube, substantially as described.

2. The process herein described of making paper receptacles, said process consisting in forming a tapered tube of paper or other suitable material, cutting the tube into sections, the alternate sections being cut to

form the bodies of the receptacles, and the other sections being cut to form the reinforcing ring-sections, passing the large ends of the ring-sections over the smaller ends of 5 said body-sections and securing the former to the opposite ends of the body-sections, substantially as described.

In testimony whereof I have signed my name to this specification in the presence of two subscribing witnesses.

JAMES C. KIMSEY.
